DIGITAL COMPARATOR FOR A LOW DROPOUT (LDO) REGULATOR

CROSS-REFERENCE TO RELATED APPLICATIONS

This application is a U.S. National Phase of International Application No. PCT/SG2020/050174, filed Mar. 27, 2020, which claims the benefit of Singapore Application No. SG10201902838Y, filed Mar. 29, 2019, both of which are hereby incorporated by reference herein in their entireties.

FIELD OF THE INVENTION

This invention relates to a digital comparator coupled to a pair of pull-up resistors and a pair of pull-down resistors whereby both pairs of resistors are coupled to an output terminal of a low dropout (LDO) regulator. In particular, the digital comparator comprises an edge detector module, a consecutive two-edge detector module and a consecutive three-edge detector module whereby the edge detector module is configured to receive two clock signals as inputs and after being processed by these three modules, to pull-up or pull-down the resistors at the output terminal of the LDO regulator based on the rising and falling edges of the received clock signals.

SUMMARY OF THE PRIOR ART

Low dropout (LDO) regulators are voltage regulators that may be used to make high speed adjustments to the power supplied to a load of a circuit or system. A conventional analogue LDO regulator comprises an amplifier that is used to drive a gate terminal of an output transistor which is powered by an input power supply. The output transistor is then configured to provide a regulated output voltage to a load. The regulated output voltage is compared with a reference voltage by the amplifier and it is this negative feedback that sets the voltage at the gate terminal so that the output voltage is regulated.

In particular, ultra-low power output-capacitorless LDO regulators are widely used in system-on-chip (SoC) designs as SoC designs typically have power sources with energy density limitations. As such, those skilled in the art are investigating the use of digital LDO regulators in SoC designs as these digital LDO regulators are compatible with scalable processes and voltage supplies. The downside is that there is an inherent trade-off between power consumption and transient response when this approach is adopted. In order to address this and to achieve better transient responses, hybrid controlled LDOs were proposed by those skilled in the art.

However, in the designs proposed so far, a large coupling capacitor or internal charge pumps are required to be used and this severely narrows the voltage supply range of the hybrid controlled LDO. Other techniques such as multiple-clock or dynamic-clock schemes have also been proposed, but were not successful as the designs comprise other types of power-hungry supportive blocks that cause the overall power performance to degrade significantly.

Apart from this, as SoC technology progresses into sub-threshold design processes, the noise level of digital LDOs become troublesome and affect the load circuit's operational reliability due to the limited dynamic range of its load. To achieve low noise performance, dynamic dead zone control and analogue type control methods such as PWM control method and switched-capacitor resistance methods have

been proposed. However, the dynamic dead zone design involves a long settling time in its transient response and this is mainly attributed to the dead zone tuning period. Hence, it can be said that while the noise performance of LDOs may be improved upon, this results in a compromise on the maximum current range of its load.

For the above reasons, those skilled in the art are constantly striving to come up with a digital comparator that has ultra-low power consumption and fast transient response times.

SUMMARY OF THE INVENTION

The above and other problems are solved and an advance in the art is made by circuits and apparatuses provided by embodiments in accordance with the invention.

A first advantage of embodiments of circuits and apparatuses in accordance with the invention is that the digital comparator consumes ultra-low power as compared to existing digital comparators.

A second advantage of embodiments of circuits and apparatuses in accordance with the invention is that an LDO regulator comprising the digital comparator is able to achieve a large load dynamic range.

A third advantage of embodiments of circuits and apparatuses in accordance with the invention is that an LDO regulator comprising the digital comparator utilizes a small on-chip capacitor thereby reducing the overall size of the SoC design and increases the range of the voltage supply.

The above advantages are provided by embodiments of a system in accordance with the invention operating in the following manner.

According to a first aspect of the invention, a digital comparator coupled to a pair of pull-up resistors and a pair of pull-down resistors whereby both pairs of resistors are coupled to a gate terminal of an output stage is disclosed, the digital comparator comprising: a single-edge detector stage configured to detect a first rising edge in a received first digital signal, and to detect a first falling edge in a received second digital signal, whereby when the first rising edge is detected and when the first falling edge is not simultaneously detected, a detector node is set to a low voltage level, and when the first falling edge is detected, the detector node is set to a high voltage level; a consecutive two-edge detector stage coupled to the single-edge detector stage, the consecutive two-edge detector stage configured to detect the voltage level of the detector node, a consecutive second rising edge in the received first digital signal and a consecutive second falling edge in the received second digital signal, whereby when the consecutive second rising edge is detected and when the voltage level of the detector node is simultaneously detected to be at a low voltage level, the consecutive two-edge detector stage causes one of the pair of pull-up resistors to pull up a voltage at the gate terminal, and when the consecutive second falling edge is detected and when the voltage level of the detector node is simultaneously detected to be at a high voltage level, the consecutive two-edge detector stage causes one of the pair of pull-down resistors to pull down the voltage at the gate terminal; a consecutive three-edge detector stage coupled to the single-edge and the consecutive two-edge detector stages, the consecutive three-edge detector stage configured to detect the voltage level of the detector node, a consecutive third rising edge in the received first digital signal and a consecutive third falling edge in the received second digital signal, whereby when the consecutive third rising edge is detected and when the voltage level of the detector node is

simultaneously detected to be at a low voltage level, the consecutive three-edge detector stage causes the other one of the pair of pull-up resistors to pull up the voltage at the gate terminal, and when the consecutive third falling edge is detected and when the voltage level of the detector node is simultaneously detected to be at a high voltage level, the consecutive three-edge detector stage causes the other one of the pair of pull-down resistors to pull down the voltage at the gate terminal.

With reference to the first aspect, when the consecutive two-edge detector stage and the consecutive three-edge detector stage detects a high voltage level at the detector node, the consecutive two-edge and three-edge detector stages cause the pair of pull-up resistors to be disabled.

With reference to the first aspect, when the consecutive two-edge detector stage and the consecutive three-edge detector stage detects a low voltage level at the detector node, the consecutive two-edge and three-edge detector stages cause the pair of pull-down resistors to be disabled.

With reference to the first aspect, wherein level shifters are provided at inputs of the single-edge detector stage, at outputs of the consecutive two-edge detector and at outputs of the consecutive three-edge detector stage.

With reference to the first aspect, a digital low-dropout circuit having the digital comparator according to the first aspect is disclosed, the digital low-dropout circuit comprising: a first inverter ring oscillator that is controllable by an output voltage of the output stage to generate the first digital signal; and a second inverter ring oscillator that is controllable by a reference voltage to generate the second digital signal.

With reference to the first aspect, the digital low-dropout circuit comprises a Miller capacitor that is provided between the gate terminal and an output node of the output stage.

With reference to the first aspect, the digital low-dropout circuit comprises a feed-forward capacitor that is provided between an output node of the output stage and the input of the second inverter ring oscillator.

With reference to the first aspect, a sub-digital comparator is provided to control a pseudo-voltage of the digital comparator.

With reference to the first aspect, the sub-digital comparator comprises: a differential amplifier having a first input coupled to a voltage divider and a second input coupled to a third inverter ring oscillator that is controllable by the reference voltage.

According to a second aspect of the invention, a method of controlling a digital comparator that is coupled to a pair of pull-up resistors and a pair of pull-down resistors whereby both pairs of resistors are coupled to a gate terminal of an output stage is disclosed, the method comprising the steps of: detecting, using a single-edge detector stage, a first rising edge in a received first digital signal, and a first falling edge in a received second digital signal, whereby when the first rising edge is detected and when the first falling edge is not simultaneously detected, setting a detector node to a low voltage level, and when the first falling edge is detected, setting the detector node to a high voltage level; detecting, using a consecutive two-edge detector stage coupled to the single-edge detector stage, the voltage level of the detector node, a consecutive second rising edge in the received first digital signal and a consecutive second falling edge in the received second digital signal, whereby when the consecutive second rising edge is detected and when the voltage level of the detector node is simultaneously detected to be at a low voltage level, causing one of the pair of pull-up resistors to pull up a voltage at the gate terminal, and when

the consecutive second falling edge is detected and when the voltage level of the detector node is simultaneously detected to be at a high voltage level, causing one of the pair of pull-down resistors to pull down the voltage at the gate terminal; detecting, a consecutive three-edge detector stage coupled to the single-edge and the consecutive two-edge detector stages, the voltage level of the detector node, a consecutive third rising edge in the received first digital signal and a consecutive third falling edge in the received second digital signal, whereby when the consecutive third rising edge is detected and when the voltage level of the detector node is simultaneously detected to be at a low voltage level, causing the other one of the pair of pull-up resistors to pull up the voltage at the gate terminal, and when the consecutive third falling edge is detected and when the voltage level of the detector node is simultaneously detected to be at a high voltage level, causing the other one of the pair of pull-down resistors to pull down the voltage at the gate terminal.

With respect to the second aspect, when the consecutive two-edge detector stage and the consecutive three-edge detector stage detects a high voltage level at the detector node, the method comprises the step of causing the pair of pull-up resistors to be disabled.

With respect to the second aspect, when the consecutive two-edge detector stage and the consecutive three-edge detector stage detects a low voltage level at the detector node, the method comprises the step of causing the pair of pull-down resistors to be disabled.

With respect to the second aspect, level shifters are provided at inputs of the single-edge detector stage and at outputs of the consecutive three-edge detector stage.

FIGS. 23A, 23B and 23C illustrating the transient response of the LDO regulator in accordance with embodiments of the invention.

DETAILED DESCRIPTION

This invention relates to a digital comparator coupled to a pair of pull-up resistors and a pair of pull-down resistors whereby both pairs of resistors are coupled to an output terminal of a low dropout (LDO) regulator. In particular, the digital frequency comparator comprises an edge detector module, a consecutive two-edge detector module and a consecutive three-edge detector module whereby the edge detector module is configured to receive two clock signals as

inputs. These received signals, after being processed by these three modules, then cause the respective resistors of the LDO regulator to be pulled-up or pulled-down based on the rising and falling edges of the received clock signals.

A block diagram of a digital comparator in accordance with embodiments of the invention is illustrated in FIG. 1. Digital comparator 100 comprises an edge detector stage 105, a consecutive two-edge detector stage 110 and a consecutive three-edge detector stage 115. Edge detector stage 105 is configured to receive a first digital signal F_U and a second digital signal F_D whereby in embodiments of the invention, edge detector stage 105 is further configured to detect a rising edge in the first digital signal F_U and to detect a falling edge in the second digital signal F_D . When rising or falling edges are detected in either or both signals, edge detector stage 105 then causes a voltage level at its output node D_U to change accordingly.

The first and second digital signals F_U and F_D , and the output node D_U are coupled to the input of two-edge detector stage 110 such that the two-edge detector stage 110 is configured to cause voltage levels at its output nodes clk_{U1} and clk_{D1} to change accordingly when another consecutive rising edge in the first digital signal F_U is detected and/or when another consecutive falling edge in the second digital signal F_D is detected.

The first and second digital signals F_U and F_D , and the output node D_U are also coupled to the input of three-edge detector stage 115 such that the three-edge detector stage 115 is configured to cause voltage levels at its output nodes clk_{U2} and clk_{D2} to change accordingly when a third consecutive rising edge in the first digital signal F_U is detected and/or when a third consecutive falling edge in the second digital signal F_D is detected.

In accordance with embodiments of the invention, but not limited to this embodiment, the outputs from the two-edge detector stage 110 and the three-edge detector stage 115 may then be coupled to a pair of pull-up and to a pair pull-down resistors accordingly to control the “pull” timings of these resistors.

FIG. 2 illustrates the circuit diagrams of the edge detector stage 105, the consecutive two-edge detector stage 110 and the consecutive three-edge detector stage 115 whereby the outputs U_C , U_E , D_C and D_E of digital comparator 100 are provided to output stage 250 after the output signals U_C , U_E , D_C and D_E have been delayed and level-shifted to appropriate levels clk_{U1} , clk_{U2} , clk_{D1} and clk_{D2} to control switches 221, 222, 231 and 232 respectively. Transistors in each of these stages are coupled to either voltage supply V_{supply} or pseudo-voltage VSS_{pseudo} whereby the voltage level of VSS_{pseudo} is understood to be lower than the voltage level of V_{supply} whereby in embodiments of the invention, the voltage drop between VSS_{pseudo} and V_{supply} is about 0.8 Volts.

When switches 221 and 222 switch on, they cause pull-up resistors R_{U1} and R_{U2} to pull the gate voltage V_{gate} of power amplifier 235 up, and when switches 231 and 232 switch on, they cause pull-down resistors R_{D1} and R_{D2} to pull the gate voltage V_{gate} of power amplifier 235 down. By doing this, the digital comparator 100 is able to control the output voltage at the LDO_out node by controlling the timings of pull-up resistors R_{U1} and R_{U2} through switches 221 and 222 and the timings of pull-down resistors R_{D1} and R_{D2} through switches 231 and 232.

As illustrated in FIG. 2, edge detector stage 105 comprises sub-circuit 205a for receiving the first digital signal F_U and sub-circuit 205b for receiving the second digital signal F_D .

In embodiments of the invention, sub-circuits 205a, 210a and 215a were configured to detect rising edges in the first digital signal F_U . As such, sub-circuit 205a comprises a plurality of logic NOT gates (or inverters) and at least two N-type Metal-Oxide-Semiconductor (NMOS) transistors, M_{NU1} and M_{NU2} , that are connected in series whereby a source terminal of NMOS transistor M_{NU1} is connected to a supply voltage VSS_{pseudo} , and a drain terminal of NMOS transistor M_{NU2} is connected to a detector node D_U . The logic NOT gates are configured such that when the first digital signal F_U is provided to sub-circuit 205a, the first digital signal is delayed and inverted by the NOT gates thereby producing delayed-first digital signal FP_U . As can be seen, sub-circuit 205a is configured such that the first digital signal F_U is provided directly to NMOS transistor M_{NU1} while the delayed-first digital signal FP_U is provided to NMOS transistor M_{NU2} .

Consecutive two-edge detector stage 110 comprises sub-circuit 210a for receiving the first digital signal F_U , the delayed-first digital signal FP_U and the detector node voltage D_U . In particular, as illustrated in FIG. 2, sub-circuit 210a comprises at least three NMOS transistors, M_{NU4} , M_{NU5} and M_{NU6} that are connected in series whereby the output node U_C is provided at the drain terminal of the NMOS transistor M_{NU4} , at least two P-type Metal-Oxide-Semiconductor (PMOS) transistors, M_{PU1} and M_{PU2} , that are connected in series, a NMOS transistor M_{NU3} whose gate is switched by the voltage at the detector node D_U and has as its drain terminal output node U_B and a PMOS transistor M_{PU3} whose gate is coupled to output node U_B and drain is coupled to output node U_C . As can be seen, sub-circuit 210a is configured such that the first digital signal F_U is provided directly to NMOS transistor M_{NU6} and PMOS transistor M_{PU1} , the delayed-first digital signal FP_U is provided to NMOS transistor M_{NU5} , and the voltage at the detector node D_U is provided to PMOS transistor M_{PU2} and NMOS transistor M_{NU3} .

As for consecutive three-edge detector stage 115, this stage comprises sub-circuit 215a for receiving first digital signal F_U , the delayed-first digital signal FP_U and the voltage at node U_C . In particular, as illustrated in FIG. 2, sub-circuit 215a comprises at least two NMOS transistors, M_{NU9} and M_{NU10} that are connected in series, at least two PMOS transistors, M_{PU4} and M_{PU5} , that are connected in series, NMOS transistors M_{NU7} and M_{NU8} whereby the drain terminal of the NMOS transistor M_{NU7} (whose gate is switched by the voltage at output node U_C) has as its drain terminal output node U_D and the drain terminal of the NMOS transistor M_{NU8} (whose gate is switched by the voltage at output node U_D) has as its drain terminal output node U_E . As can be seen, sub-circuit 215a is configured such that the first digital signal F_U is provided directly to NMOS transistor M_{NU10} and PMOS transistor M_{PU5} , the delayed-first digital signal FP_U is provided to NMOS transistor M_{NU9} , and the voltage at the output node U_C is provided to PMOS transistor M_{PU4} and NMOS transistor M_{NU7} .

Hence, it can be said that when a first digital signal F_U is provided to sub-circuits 205a, 210a and 215a, the output from these sub-circuits may be obtained from output nodes U_E and U_C .

Sub-circuits 205b, 210b and 215b comprise of an almost similar configuration as that of sub-circuits 205a, 210a and 215a respectively. However, as sub-circuits 205b, 210b and 215b were configured to detect a falling edge in the second digital signal F_D , the type of the transistors used in 205b, 210b and 215b differs from that of sub-circuits 205a, 210a and 215a.

In particular, sub-circuit 205b similarly comprises a plurality of logic NOT gates (or inverters) and at least two PMOS transistors, M_{PD1} and M_{PD2} , that are connected in series whereby a source terminal of PMOS transistor M_{PD1} is connected to a supply voltage V_{Supply} and a drain terminal of PMOS transistor M_{PD2} is connected to the detector node D_U . The logic NOT gates are configured such that when the second digital signal F_D is provided to sub-circuit 205b, the second digital signal is delayed and inverted by the NOT gates thereby producing delayed-second digital signal FP_D . As can be seen, sub-circuit 205b is configured such that the second digital signal F_D is provided directly to PMOS transistor M_{PD1} while the delayed-second digital signal FP_D is provided to PMOS transistor M_{PD2} .

Sub-circuit 210b is then configured to receive the second digital signal F_D , the delayed-second digital signal FP_D and the detector node voltage D_U . In particular, as illustrated in FIG. 2, sub-circuit 210b comprises at least three PMOS transistors, M_{PD4} , M_{PD5} and M_{PD6} that are connected in series whereby the output node D_C is provided at the drain terminal of the PMOS transistor M_{PD6} , at least two NMOS transistors, M_{ND1} and M_{ND2} , that are connected in series, a PMOS transistor M_{PD5} whose gate is switched by the voltage at the detector node D_U and has as its drain terminal output node D_B and a NMOS transistor M_{ND3} whose gate is coupled to output node D_B and drain is coupled to output node D_C . As can be seen, sub-circuit 210b is configured such that the second digital signal F_D is provided directly to PMOS transistor M_{PD4} and NMOS transistor M_{ND2} , the delayed-second digital signal FP_D is provided to PMOS transistor M_{PD5} , and the voltage at the detector node D_U is provided to PMOS transistor M_{PD3} and NMOS transistor M_{ND1} .

As for sub-circuit 215b, this circuit is configured to receive second digital signal F_D , the delayed-second digital signal FP_D and the voltage at node D_C . In particular, as illustrated in FIG. 2, sub-circuit 215b comprises at least two PMOS transistors, M_{PD9} and M_{PD10} that are connected in series, at least two NMOS transistors, M_{ND4} and M_{ND5} , that are connected in series, PMOS transistors M_{PD7} and M_{PD8} whereby the drain terminal of the PMOS transistor M_{PD7} (whose gate is switched by the voltage at output node D_C) has as its drain terminal output node D_D and the drain terminal of the PMOS transistor M_{PD5} (whose gate is switched by the voltage at output node D_D) has as its drain terminal output node D_E . As can be seen, sub-circuit 215b is configured such that the second digital signal F_D is provided directly to PMOS transistor M_{PD10} and PMOS transistor M_{ND5} , the delayed-second digital signal FP_D is provided to PMOS transistor M_{PD9} , and the voltage at the output node D_C is provided to NMOS transistor M_{ND4} and PMOS transistor M_{PD7} .

Hence, it can be said that when the second digital signal F_D is provided to sub-circuits 205b, 210b and 215b, the output from these sub-circuits may be obtained from output nodes D_E and D_C .

In order to better understand the detailed workings of these sub-circuits, reference is made to the timing diagrams illustrated in FIGS. 3-10. FIG. 3 illustrates the timing diagrams of sub-circuits 205a, 210a and 215a when first and second digital signals F_U and F_D are provided to sub-circuits 205a, 210a and 215a. In particular, this timing diagram provides an overview of the key events/steps 301-305 that occur.

At step 301, as illustrated in FIG. 4, it can be seen that due to the logic NOT gates in sub-circuit 205a, a delay of period T_2 exists between the first digital signal F_U and the inverted

delayed-first digital signal FP_U . Due to this delay, after a rising edge occurs for signal F_U , the signal FP_U only starts falling after the period T_2 has lapsed. During this period T_2 , as both signals F_U and FP_U are “high”, this causes NMOS transistors M_{NU1} and M_{NU2} to switch on and as the second digital signal F_D is “low”, this causes one of PMOS transistors M_{PD1} and M_{PD2} to switch off. As a result, the voltage at detector node D_U is triggered to become low, i.e. the voltage at detector node D_U is set to $V_{SS_{pseudo}}$. It is useful at this stage to recap that the voltage level of $V_{SS_{pseudo}}$ is understood to be lower than the voltage level of V_{supply} whereby in embodiments of the invention, the voltage drop between $V_{SS_{pseudo}}$ and V_{supply} is about 0.8 Volts.

At step 302, as illustrated in FIG. 5, it can be seen that due to the logic NOT gates in sub-circuit 205b, a delay of period T_1 similarly exists between the second digital signal F_D and the inverted delayed-first digital signal FP_D . Due to this delay, after a falling edge occurs for signal F_D , the signal FP_D only starts rising after the period T_1 has lapsed. During this period T_1 , as both signals F_D and FP_D are “low”, this causes PMOS transistors M_{PD1} and M_{PD2} to switch on and as the first digital signal F_U is “high”, this causes one of NMOS transistors M_{NU1} and M_{NU2} to switch off. As a result, the voltage at detector node D_U is triggered to become high, i.e. the voltage at detector node D_U is set to V_{supply} .

With reference to FIG. 3, it can be seen that after step 302, the second digital signal F_D does not have another falling edge until step 305. After step 302, a first rising edge 300a occurs at digital signal F_U causing detector node D_U to become low. This in turn switches PMOS transistor M_{PU2} on.

At step 302a, as illustrated in FIG. 6, when signal F_U becomes low and when signal FP_U becomes low for a period of T_2 , this causes PMOS transistor M_{PU1} to switch on thereby causing a voltage level at node U_B to become high.

Subsequently, as illustrated in FIG. 7, a second rising edge 300b occurs for digital signal F_U at step 303 whereby for a period of time T_2 , signals F_U and FP_U are both high causing the voltage level at node U_C to become low, which in turn after being processed by inverters and a level shifter, causes a voltage level at output node clk_{U1} to become low as well.

As a falling edge is not detected at the second digital signal F_D , when the signal F_U becomes low (and signal FP_U is low as well for a period of time T_2), this causes the voltage at node U_D to become high. This takes place at step 303a as illustrated in FIG. 8.

Subsequently, as illustrated in FIG. 9, a third rising edge 300c occurs for digital signal F_U at step 304. This causes the voltage level at node U_E to become low as NMOS transistors M_{NU8} , M_{NU9} , and M_{NU10} are switched on. After the voltage level at node U_E has been processed by inverters and a level shifter, this causes a voltage level at output node clk_{U2} to become low as well.

At step 305, as illustrated in FIG. 10, a falling edge is detected at the second digital signal F_D (and signal FP_D remains low as well for a period of time T_1) and this causes the voltage at detector node D_U to become high. As the voltage at detector node D_U becomes high, it causes the voltage level at node U_D to become low, which in turn triggers the voltage level at node U_C to become high. This then in turn causes the voltage level at U_D to become low and this causes the voltage level at node U_E to become high. As a result, the voltage levels at output nodes clk_{U1} and clk_{U2} both become high.

For completeness, the timing diagrams of sub-circuits 205b, 210b and 215b when first and second digital signals F_U and F_D are provided to these sub-circuits will be dis-

cussed in FIGS. 11-18. In particular, this timing diagram provides an overview of the key events/steps 1101-1105 that occur in these sub-circuits.

At step 1101, as illustrated in FIG. 12, a delay of period T_1 exists between the second digital signal F_D and the inverted delayed-second digital signal FP_D . Due to this delay, after a falling edge occurs for signal F_D , the signal FP_D only starts falling after the period T_1 has lapsed. During this period T_1 , as both signals F_D and FP_D are “low”, this causes PMOS transistors M_{PD1} and M_{PD2} to switch on and as the first digital signal F_U is “high”, this causes one of NMOS transistors M_{NU1} and M_{NU2} to switch off. As a result, the voltage at detector node D_U is triggered to become high.

At step 1102, as illustrated in FIG. 13, it can be seen that a delay of period T_2 similarly exists between the first digital signal F_U and the inverted delayed-second digital signal FP_U . Due to this delay, after a rising edge occurs for signal F_U , the signal FP_U only starts falling after the period T_2 has lapsed. During this period T_2 , as both signals F_U and FP_U are “high”, this causes NMOS transistors M_{NU1} and M_{NU2} to switch on and as the second digital signal F_D is “low”, this causes one of PMOS transistors M_{PD1} and M_{PD2} to switch off.

As a result, the voltage at detector node D_U is triggered to become low.

After step 1102, at step 1103, a first falling edge occurs at digital signal F_D causing detector node D_U to become high. This is shown in FIG. 14. This triggering action in turn switches NMOS transistor M_{ND1} on.

At step 1103a, as illustrated in FIG. 15, when signal F_D becomes high and when signal FP_D is high as well for a period of T_1 , this causes a voltage level at node D_B to become low.

Subsequently, at a second falling edge 1501 of digital signal F_D , the voltage level at node D_C becomes high, which in turn after being processed by inverters and a level shifter, causes a voltage level at output node clk_{D1} to become high as well.

As a rising edge is not detected at the first digital signal F_U , when the signal F_D becomes high, this causes the voltage at node D_D to become low. This takes place at step 1103b as illustrated in FIG. 16.

Subsequently, as illustrated in FIG. 17, a third falling edge 1701 occurs for digital signal F_D at step 1104. This causes the voltage level at node D_E to become high as PMOS transistors M_{PD8} , M_{PD9} , and M_{I0} are switched on. After the voltage level at node D_E has been processed by inverters and a level shifter, this causes a voltage level at output node clk_{D2} to become high as well.

At step 1105, as illustrated in FIG. 18, a rising edge is detected at the first digital signal F_U and this causes the voltage at detector node D_U to become low. As the voltage at detector node D_U becomes low, it causes the voltage level at node D_R to become high, which in turn triggers the voltage level at node D_C to become low. This then in turn causes the voltage level at D_D to become high and this causes the voltage level at node D_E to become low. As a result, the voltage levels at output nodes clk_{D1} and clk_{D2} both become low.

Hence, as illustrated in the timing diagrams in FIGS. 3-18, sub-circuits 205a/b, 210a/b, and 215a/b may be used to pull up the pair of pull-up resistors R_{U1} and R_{U2} and to pull down the pair of pull-down resistors R_{D1} and R_{D2} when certain signals are received by these sub-circuits.

FIG. 19 illustrates a circuit diagram of hybrid LDO regulator 1900 that includes digital comparator 200, 3-stage

inverter ring oscillators (VCOs) VCO_D and VCO_U , a push-pull resistor array 1905, amplifier 220 and VSS_{pseudo_bias} comparator circuit 1915.

In embodiments of the invention, the VCOs VCO_D and VCO_U are configured to generate clocks with frequencies that are proportional to the differential voltage inputs. As illustrated in FIG. 19, a pair of common source NMOS transistors, NM_1 and NM_2 are utilized to set the tail currents of two subthreshold inverter ring oscillators, VCO_D and VCO_U . In embodiments of the invention, through simulation, it was found that these VCOs were able to generate 15 MHz oscillating clock signals with oscillating amplitudes between 0.55 V and 0.35 V while drawing only 20 nA of current when a 0.55 V voltage supply was used.

Two digital clock signals, F_U and F_D , are provided to comparator 200 by VCOs VCO_D and VCO_U , whereby rising/falling edge sequence information of the digital clock signals, F_U and F_D are extracted by comparator 200 and used to control a push-pull resistor array to control the gate voltage of amplifier 220.

In order to reduce the amount of power consumed by the hybrid-LDO, digital comparator 200's supply voltage VSS_{pseudo} is controlled by VSS_{pseudo_bias} comparator circuit 1915 to ensure that sure that digital comparator 200's voltage drop is no more than 3-times (3 $\times$) of the mentioned oscillating amplitude, and does not constitute the whole supply. Another ring oscillator, VCO_F , which is identical to VCOs VCO_U and VCO_D , is added to circuit 1915 to provide a reference voltage to differential amplifier AMP₁. Differential amplifier AMP₁ is configured to control NMOS switch NM_{VSS} such that the current drawn by comparator 200 may be adjusted to ensure that a specific voltage drop exists in comparator 200 between its supply voltage and pseudo supply voltage. When LDO 1900 is in a stable state, digital clock signals F_U and F_D would be almost the same and as a result, LDO 1900 would consume ultra-low power. This means that when LDO 1900 is in a stable state, the push-pull resistor array would be totally OFF and only the differential VCOs and comparator 200 would be active.

In order to ensure that hybrid-LDO 1900 has a stable transient response or a stable output voltage, the dominant pole at its output is maintained at the gate node of amplifier 220 by a Miller capacitor C_{Miller} 1910 (which is connected between the gate node and the output node of amplifier 220). The use of capacitor 1910 also improves the LDO's transient response as changes to its output voltage would be coupled to amplifier 220's gate. For example, when the output voltage of amplifier 220 increases, C_{Miller} 1910 pulls up the voltage at the V_{gate} node simultaneously, which in turn reduces the current flowing through amplifier 220. This feedback loop compensates for voltage changes at the output of amplifier 220 and this helps to stabilize the output voltage. To further enhance the transient response of the hybrid-LDO, a feedforward capacitor C_{FD} 1950 is added to speed up the VCO's frequency response time. When the output voltage of amplifier 220 changes, C_{FD} 1950 feed forwards the voltage change to VCO_D and causes signal F_D to change accordingly. Without C_{FD} 1950, the output voltage of amplifier 220 will affect the voltage of V_{FB} which in turn controls the voltage at VCO_U . When this happens, signal F_U changes accordingly and in general, this takes a much longer time.

FIG. 20 illustrates a simulated plot of voltage VSS_{pseudo} and the current consumed by comparator 200 vs. supply voltage V_{supply} when comparator 200 is used in LDO 1900.

It can be seen that the voltage drop between VSS_{pseudo} and V_{supply} is about 0.8 V when the supply voltage is more than 0.7 V.

FIG. 21 shows the simulated waveforms of LDO 1900 from its start up when it's output deviates from a target voltage and the stable mode when the LDO has stabilized and its output is regulated. When $V_{FD} > V_{ref}$, the frequency of signal F_U is higher than the frequency of signal F_D .

When two consecutive rising edges are detected at signal 10 F_U and when these two rising edges are located in between two F_D falling edges, a pull-up resistor R_{U1} that is connected to the gate of the PMOS gate will charge gate's voltage accordingly.

Further, if three consecutive rising edges are detected at signal F_U , a pull-up resistor R_{U2} that is connected to the gate of the PMOS transistor's gate will charge the gate's voltage as well. Hence, when the voltage error at the LDO's output is small, only pull-up resistor R_{U1} is required to discretely charge the gate voltage of the PMOS transistor, and the equivalent pole at the PMOS transistor's gate is suppressed at a low frequency. However, if the LDO is in transient response function mode, resistor R_{U2} will also be connected to the gate of the PMOS transistor to charge its gate faster in order to reduce the LDO's settling time. In this way, the settling time is shortened and the LDO's stability is maintained.

When $V_{FB} < V_{ref}$ the frequency of signal F_U is lower than the frequency of signal F_D as such, resistors R_D , and R_{D2} 30 may then be used to pull down the voltage at the PMOS transistor's gate.

After a certain period of time has lapsed, the LDO's output voltage would have been regulated to the required value, as such, the frequencies of signals F_U and F_D would 35 be almost the same, and output nodes $clk_{U1/2}$ and $clk_{D1/2}$ would be in their disabled states. Hence, only the VCOs and the digital comparator would be active, and as a result, the LDO consumes very low power.

Experimental Results

In this experiment, LDO 1900 was fabricated using a 65 nm CMOS process, with 400 nA quiescent current and a 20 pF capacitor. FIG. 22 illustrates the performance of the simulated LDO whereby plot 2205 shows that the output of the LDO remains stable even though the input of the LDO 45 gradually increases and plot 2210 shows that the output of the LDO remains stable even though the input of the LDO gradually decreased.

FIG. 23 illustrates the measured performance of the LDO's transient response when the current of the LDO I_{load} 50 is stepped from 0.5 mA to 10.5/20.5/30.5 mA, respectively and back to 0.5 mA with an edging time of 10 ns. As only a 10 pF load capacitor was used, 180/220/250 mV undershoot and 180/270/300 mV overshoot were achieved, respectively. The undershoot and the overshoot settling time 55 was measured to be 0.5 μ s and 6 μ s, respectively. In particular, FIG. 23A illustrates the transient response of the LDO when the load current shifts between 0.5 mA and 10.5 mA; FIG. 23B illustrates the transient response of the LDO when the load current shifts between 0.5 mA and 20.5 mA; 60 and FIG. 23C illustrates the transient response of the LDO when the load current shifts between 0.5 mA and 30.5 mA.

The DC characteristics of the LDO are summarized in Table 1 below whereby the line regulation and load regulation were measured to be 2.5 mV/V and 0.5 mV/mA, 65 respectively. When the load current was at 630 nA, a larger than 99.9% current efficiency was achieved in 10 mA load regulation current.

TABLE 1

450 mV output	Quiescent current	Load regulation (0~10 mA)	Line regulation (0.6 V~1.2 V, 10 mA load)	
TYP, 25 degree	633 nA	500 μ V/mA	2.5 mV/V	
SS, 0 degree	660 nA	470 μ V/mA	4.2 mV/V	
FF, 50 degree	608 nA	1.3 mV/mA	10 mV/V	

The performance of an LDO designed in accordance with embodiments of the invention is compared against other designs known in the art in Table 2 below. Table 2 shows that with 400 nA quiescent current and a 0.5V supply, a 1,000,000 $\times$ load dynamic range and a 0.004 ps Figure of Merit (FOM) was achievable with the lowest quiescent current, largest load dynamic range and smallest on-chip capacitor compared to other state-of-art digital/hybrid control LDOs. For FOM comparisons, the proposed LDO in 65 nm technology achieved 2 orders of better performance than the LDOs designed using the 40 nm and 65 nm processes and even has a better value than the one designed using the 28 nm process (which is a more matured process and should have power and speed advantages when FOM calculation is performed).

The above is a description of embodiments of a system and method in accordance with the present invention as set forth in the following claims. It is envisioned that others may and will design alternatives that fall within the scope of the following claims.

The invention claimed is:

1. A digital comparator coupled to a pair of pull-up resistors and a pair of pull-down resistors whereby both 55 pairs of resistors are coupled to a gate terminal of an output stage, the digital comparator comprising:

a single-edge detector stage configured to detect a first rising edge in a received first digital signal, and to detect a first falling edge in a received second digital signal, whereby when the first rising edge is detected and when the first falling edge is not simultaneously detected, a detector node is set to a low voltage level, and when the first falling edge is detected, the detector node is set to a high voltage level;

a consecutive two-edge detector stage coupled to the single-edge detector stage, the consecutive two-edge

whereby when the consecutive third rising edge is detected and when the voltage level of the detector node is simultaneously detected to be at the low voltage level, the consecutive three-edge detector stage causes the other one of the pair of pull-up resistors to pull up the voltage at the gate terminal, and

when the consecutive third falling edge is detected and when the voltage level of the detector node is simultaneously detected to be at the high voltage level, the consecutive three-edge detector stage causes the other one of the pair of pull-down resistors to pull down the voltage at the gate terminal.

2. The digital comparator according to claim 1, whereby when the consecutive two-edge detector stage and the consecutive three-edge detector stage detect a high voltage level at the detector node, the consecutive two-edge and three-edge detector stages cause the pair of pull-up resistors to be disabled.

3. The digital comparator according to claim 1, whereby when the consecutive two-edge detector stage and the con-

15

secutive three-edge detector stage detect a low voltage level at the detector node, the consecutive two-edge and three-edge detector stages cause the pair of pull-down resistors to be disabled.

4. The digital comparator according to claim **1**, wherein level shifters are provided at inputs of the single-edge detector stage, at outputs of the consecutive two-edge detector stage and at outputs of the consecutive three-edge detector stage. 5

5. A digital low-dropout circuit having the digital comparator according to claim **1**, the digital low-dropout circuit using the output stage to generate a stable output voltage, the digital low-dropout circuit comprising: 10

a first inverter ring oscillator that is controllable by an output voltage of the output stage to generate the first 15 digital signal; and

a second inverter ring oscillator that is controllable by a reference voltage to generate the second digital signal.

6. The digital low-dropout circuit according to claim **5**, wherein a sub-digital comparator is provided to control a 20 pseudo-voltage of the digital comparator.

7. The digital low-dropout circuit according to claim **6**, whereby the sub-digital comparator comprises:

a differential amplifier having a first input coupled to a voltage divider and a second input coupled to a third 25 inverter ring oscillator that is controllable by the reference voltage.

8. The digital low-dropout circuit according to claim **5**, wherein a Miller capacitor is provided between the gate 30 terminal and an output node of the output stage.

9. The digital low-dropout circuit according to claim **5**, wherein a feed-forward capacitor is provided between an output node of the output stage and an input of the second inverter ring oscillator.

10. A method of controlling a digital comparator that is coupled to a pair of pull-up resistors and a pair of pull-down resistors whereby both pairs of resistors are coupled to a gate terminal of an output stage, the method comprising:

detecting, using a single-edge detector stage, a first rising edge in a received first digital signal, and a first falling edge in a received second digital signal, whereby when the first rising edge is detected and when the first falling edge is not simultaneously detected, setting a detector node to a low voltage level, and when the first falling edge is detected, setting the detector node to a high voltage level;

detecting, using a consecutive two-edge detector stage coupled to the single-edge detector stage, a voltage level of the detector node, a consecutive second rising 45

16

edge in the received first digital signal and a consecutive second falling edge in the received second digital signal,

whereby when the consecutive second rising edge is detected and when the voltage level of the detector node is simultaneously detected to be at the low voltage level, causing one of the pair of pull-up resistors to pull up a voltage at the gate terminal, and

when the consecutive second falling edge is detected and when the voltage level of the detector node is simultaneously detected to be at the high voltage level, causing one of the pair of pull-down resistors to pull down the voltage at the gate terminal;

detecting, a consecutive three-edge detector stage coupled to the single-edge and the consecutive two-edge detector stages, the voltage level of the detector node, a consecutive third rising edge in the received first digital signal and a consecutive third falling edge in the received second digital signal,

whereby when the consecutive third rising edge is detected and when the voltage level of the detector node is simultaneously detected to be at the low voltage level, causing the other one of the pair of pull-up resistors to pull up the voltage at the gate terminal, and

when the consecutive third falling edge is detected and when the voltage level of the detector node is simultaneously detected to be at the high voltage level, causing the other one of the pair of pull-down resistors to pull down the voltage at the gate terminal.

11. The method according to claim **10**, whereby when the consecutive two-edge detector stage and the consecutive three-edge detector stage detect a high voltage level at the detector node, the method comprises a step of causing the pair of pull-up resistors to be disabled.

12. The method according to claim **10**, whereby when the consecutive two-edge detector stage and the consecutive three-edge detector stage detect a low voltage level at the detector node, the method comprises a step of causing the pair of pull-down resistors to be disabled.

13. The method according to claim **10**, wherein level shifters are provided at inputs of the single-edge detector stage, at outputs of the consecutive two-edge detector and at outputs of the consecutive three-edge detector stage.
